UNITED STATES PATENT OFFICE.

ALBERT W. CHASE, OF CATSKILL, NEW YORK.

INTERNAL-COMBUSTION ENGINE.

1,411,710.

Specification of Letters Patent.

Patented Apr. 4, 1922.

Application filed October 18, 1919. Serial No. 331,629.

To all whom it may concern:

Be it known that I, ALBERT W. CHASE, a citizen of the United States, and a resident of the town of Catskill, county of Greene, 5 and State of New York, have invented an Improvement in Internal-Combustion Engines, of which the following is a specification.

This invention relates to internal combustion engines.

An important object of the invention is to provide improved means for admitting the gaseous charge to the cylinder and exhausting the products of combustion therefrom.

15 The character of the invention may be best understood by reference to the following description of an illustrative embodiment thereof shown in the accompanying drawings wherein like characters refer to like parts throughout the several views.

The engine here shown in which the illustrative embodiment of the invention is incorporated is of the four stroke cycle type.

25 Fig. 1 is a partial perspective view, with certain parts broken away to reveal the interior and certain parts in section, of the engine cylinder with piston and valves therein.

30 Figs. 2 to 9 inclusive are longitudinal sectional views through one cylinder at right angles to the crank shaft with the piston and valves therein at various positions of their strokes in passing through the four strokes of explosion, exhaust, charge intake, and 35 compression, the crank case and contained parts being broken away in Fig. 2, but shown in section in the remaining figures, and with the crank at various angular positions to correspond to the positions of the piston.

40 Referring to the drawings, the illustrative engine there shown comprises a cylinder 1 somewhat elongated to provide a slideway for the piston and associated valves below the combustion chamber.

45 An outwardly curved skirt 3, here shown as integral with the cylinder casting, forms the upper portion of the crank case and terminates in a rib or flange 4, any suitable means being provided for the convenient attachment and securement of the entire engine structure upon a suitable foundation or support. The lower portion 5 of the crank case is attached to the upper portion 3 and as here shown has a rib or flange 6 abutting the 55 rib or flange 4.

Exhaust ports for the eduction of the

burnt products of combustion are shown at 7, on opposite sides of the cylinder and delivering the products of combustion to an exhaust manifold 8, in the usual manner. 60

The cylinder casting extends upward above the exhaust ports and the exhaust manifold with an interior diameter uniform with that of the combustion space, and is closed by a cylinder head casting 9 having a depending cylindrical skirt 10 interiorly spaced from the upper portion of the cylinder itself to provide an annular slideway or guide for the exhaust valve sleeve later to be more specifically referred to. 70

The cylinder head casting 9 is continued inwardly and upwardly centrally of the cylinder in a cup-shaped or concave portion 11 providing a clearance space and ignition chamber 12 opening downwardly into the cylinder, and the walls of the cup-shaped or concave portion are continued upwardly in tubular form as shown at 13 for the reception of a spark plug 14, freely inserted therethrough and secured in exposed position of 80 its sparking points in the ignition chamber through a screw threaded aperture extending from the tubular portion through the end wall of the cup-shaped portion of the casting, all in the usual manner. 85

The customary water jacket 15 is provided around the engine cylinder surrounding the combustion chamber and is extended upward about the exhaust manifold and communicates with a water jacket 16 in the cylinder head casting, the latter being closed by a cap 17 held in place in the usual manner by a screw threaded nut upon the central tubular portion of the cylinder head casting. 90

In the illustrative embodiment of my invention here shown, the combustible mixture forming the explosive charge is preferably introduced first into the crank case of the engine and thence up through the interior of the piston into the cylinder itself where it 100 is compressed upon the upward stroke of the piston and ignited in the usual manner. When the charge is introduced in this manner, my invention is particularly applicable to multi-cylinder engines, it being the desirable practice to provide a common crank case for the several cylinders, so that the explosive mixture while in the crank case is not subject to fluctuating pressures due to the reciprocation of a single piston but is at 105 all times at the substantially atmospheric pressure at which it entered the crank case, 110

due to the compensating action of oppositely moving pistons. The drawings of the illustrative embodiment of my invention show a section longitudinally through one of such cylinders and continued through the common crank case.

The piston 18 is connected in the usual manner by rod 19 with the crank shaft 20.

The explosive mixture formed in a carburetor or other charge forming device in the usual manner is introduced into the crank case through the inlet aperture 21 therein and from the crank case is delivered upwardly into the engine cylinders. The introduction of the explosive mixture to the crank case and its delivery therefrom to the engine cylinders occurs only upon and by reason of the creation of pressures below atmospheric in the respective engine cylinders due to the suction strokes of the pistons therein. The crank case so far as the delivery of the explosive mixture to the engine cylinders is concerned, therefore, functions merely as a charge inlet manifold.

To control the delivery of the explosive mixture to the engine cylinders and the eduction of the products of combustion therefrom, charge inlet and exhaust valves of novel construction and arrangement in cooperative relation with each other and with the working piston are provided, having the advantage among others, of being operated by the direct action of the expanding gases under combustion upon the valves themselves and by the movement of the piston acquired by the action of such expanding gases thereon, and hence requiring no mechanically moving parts transmitting movement to the valves from the power shaft or other moving part of the engine.

The illustrative engine here shown is of the vertical cylinder type although my invention is equally applicable to engines in which the cylinders are disposed horizontally or at any desired angle. The stroke of the piston and other moving parts toward the cylinder head will be termed their inward stroke and their stroke in the opposite direction will be termed their outward stroke, while location of parts will be defined as inward or outward relative to their positions longitudinally of the cylinder adjacent or remote from the cylinder head, and the terms radially inward and radially outward used to define the location of certain parts extending inwardly and outwardly transversely of the cylinder.

In the illustrative embodiment of the invention shown in the drawings, the valves are in the form of cylindrical sleeves within the engine cylinder. The exhaust valve, indicated by numeral 22 is a thin metallic cylinder or sleeve having oppositely disposed ports 23 near its inward end to register with the eduction ports 7 in the engine cylinder,

the valve being designed to slidily engage the interior wall of the engine cylinder. The outward limit of movement of the exhaust valve is that shown in Figs. 4 and 5 and in which the ports 23 in the valve register with the ports 7 in the engine cylinder. Its inward limit of movement is that shown in Figs. 2, 3, 6, 7, 8, and 9, and in which, it will be observed, the valve with its ports 23 extends into the annular recess between the cylinder wall above the exhaust manifold and the depending skirt 10 of the cylinder head casting, the exhaust ports 7 of the engine cylinder thus being closed by the imperforate portions of the valve sleeve. A packing ring 24 is provided in the depending skirt 10 of the cylinder head casting at its lower edge adjacent the combustion chamber and bearing radially against the valve sleeve. It is apparent that with the construction of valve sleeve and arrangement of cooperating parts such as the recessed cylinder head with its packing, here shown, pressure leakages from the engine cylinder are reduced to a minimum and that a high degree of compression is attainable.

The charge inlet valve is also here shown in the form of a metallic cylinder or sleeve 25. Charge inlet ports 26 in the inlet valve sleeve near its inward edge are provided to register with ports 27 in the cylindrical skirt of the engine piston just outwardly of its head and constituting delivery passages for the charge from the interior of the piston. The ports in the valve and the piston are made of substantially the same extent circumferentially and preferably around the entire circumference of each save for the separating bridge pieces necessary to maintain the proper strength of the valve and piston as a whole, in order that there may be a rapid delivery of the explosive mixture and hence a full charge upon each suction or charging stroke of the piston. It will be observed that there is no actual delivery of the explosive mixture to the combustion space of the engine cylinder, even though the ports in the valve and piston are in registry, until the piston has moved relative to the valve a sufficient distance to position the piston head outwardly of the inward edge of the ports in the valve, in which relative position of the parts the explosive mixture passes from the interior of the piston through its ports 27, thence it traverses the ports 26 in the inlet valve and is deflected inwardly across the top of the piston head to the combustion space of the cylinder. The relative position of the piston and inlet valve sleeve obstructing the entrance of a charge to the combustion space of the cylinder is shown in Figs. 2, 3, 4, 5, 6, and 9, while the relative position of the parts delivering the charge is shown in Figs. 7 and 8.

The ports 26 in the inlet valve sleeve are

formed of substantially greater extent longitudinally, that is in the direction of movement of the piston, than are the ports 27 in the piston in order that the piston ports may be in register with the valve ports and the piston head clear of the inward edge of the valve ports throughout the major portion of the movement of the piston relative to the valve which occurs on the suction stroke of the piston, as will presently be more fully set forth, thus causing a delivery of the explosive mixture throughout substantially the entire suction stroke.

It will be observed from the cooperative assembly and arrangement of the parts thus far described that the exhaust valve sleeve must be moved inwardly to close the exhaust ports and outwardly to open the same and must be held stationary to maintain the ports in open or closed position, and that the inlet valve sleeve and piston must be moved relative to each other in one direction to open the charge inlet ports and in the opposite direction to close the same, and that they must remain relatively immovable to maintain the inlet ports in open or closed position, which obviously means simultaneous movement of the inlet valve sleeve with the piston. In the illustrative embodiment of my invention here shown the means now to be described are provided for producing these relative and simultaneous movements of the parts.

The exhaust valve sleeve terminates at its outward end as shown in a radially inwardly projecting ring head or flange 28 having a sliding engagement upon the exterior cylindrical surface of the inlet valve sleeve as shown more particularly in Fig. 1, while the inlet valve sleeve has at its inward end a head or flange 29 projecting radially outward to correspondingly engage the interior of the exhaust valve sleeve inwardly of the ring head thereon, as shown more particularly in Figs. 2 to 9 inclusive. The engine piston within the inlet valve sleeve has a portion of such diameter as to slidably engage the interior of the inlet valve sleeve, the relative movement between these parts controlling the charge inlet ports as heretofore set forth, and a remaining lower portion 30 reduced in diameter, the two cylindrical portions of different diameters being separated by the shoulder 31. The outward edge of the reduced portion of the piston terminates in a radially outwardly extending ring or flange 32, shown in the drawings as a separate piece secured to the outward edge or skirt of the piston by screw threads and which slidably engages the interior wall of the cylinder itself. The outward end of the inlet valve sleeve terminates in a ring head having radially inwardly extending flange 33 and radially outwardly extending flange 34, the radially outwardly extending flange

being here shown as a separate piece screw threaded in place upon the valve sleeve. The radially inwardly extending flange slidably engages the reduced cylindrical surface 30 of the piston skirt between the shoulder 31 and the flange 32 while the radially outwardly extending flange slidably engages the interior wall of the cylinder itself.

By the arrangement of parts thus described, it is to be observed that the exterior surface of the exhaust valve sleeve slidably engages the interior wall of the cylinder, the radially inwardly projecting annular flange upon the outward end of the exhaust valve sleeve slidably engages the exterior cylindrical surface of the inlet valve sleeve between the flanges 29 and 34 thereon, and the radially inwardly projecting flange 33 on the inlet valve sleeve slidably engages the reduced cylindrical surface of the piston between the shoulder 31 and the flange 32 thereon, while the interior surface of the inlet valve sleeve slidably engages the cylindrical surface of the piston of large diameter.

It will also be observed that if the parts thus assembled were in sufficiently loose sliding contact to provide a rapid leakage of the air pressures developed between approaching flanges and shoulders or if other means, such for example as vent ports, for such leakage were provided, the parts may partake of relative movement, and this relative movement if of sufficient extent would bring the radially outwardly extending flanges 29 and 34 on the inlet valve sleeve alternately into contact with the flange 28 on the exhaust valve sleeve, and the shoulder 31 and flange 32 on the piston into alternate contact with the radially inwardly extending flange 33 on the inlet valve sleeve, thus forming driving connections between the parts by actual contact, so that if the piston be considered as the prime mover, it would drive the inlet valve sleeve in opposite directions by the alternate engagements referred to and the inlet valve sleeve thus driven would in turn correspondingly drive the exhaust valve sleeve.

Relative movement terminating in a driving connection between the parts is contemplated by my invention but preferably actual contact of the parts in the driving connection is avoided by the means now to be described.

The piston and inlet and exhaust valve sleeves are assembled with their surfaces in substantially air tight sliding contact. Grooves 35 are provided in the recessed or reduced portion of the piston skirt, shown in full outline in Fig. 1 and in dotted lines in the remaining figures, traversing the greater portion of the reduced cylindrical surface in the line of movement of the flange 33 of the inlet valve sleeve thereover but

ending short of the shoulder 31 and the flange 32 which determine the boundaries of the reduced portion of the piston skirt.

It is obvious from the arrangement of the 5 grooves that the piston and inlet valve sleeve may partake of free relative movement as long as the radially inwardly projecting flange 33 of the outward ring head on the inlet valve sleeve is traversing the grooves 10 35 for the air or other gaseous medium compressed between the flange 33 and the shoulder 31 by their approach to each other in one direction of relative movement of the parts escapes through the grooves to the 15 space of increasing volume between the then receding ring head 33-34 and flange 32, the compression occurring between the ring head 33-34 and the flange 32 by their approach to each other in the opposite direction of movement 20 being correspondingly relieved through the grooves. When, however, the flange 33 on the inlet valve sleeve has traversed the grooves to a point closing their outlets at either end, it is obvious that the air compressed 25 between the oppositely approaching parts has no escape outlet. From this point on the air is trapped in the space of decreasing volume and an effective air cushion formed preventing actual metallic contact of 30 the opposed parts but not interrupting the driving action of one upon the other which takes place through the medium of the thin film of air or other gaseous medium between them.

35 Grooves 36 are also provided in the exterior cylindrical surface of the inlet valve sleeve, corresponding in function to those in the reduced cylindrical skirt of the piston, and extending longitudinally of the sleeve from 40 points closely adjacent the flange 34 to and freely opening into the extended ports in the sleeve, as shown in full outline in Fig. 1 and in dotted lines in the remaining figures, the ports in the valve sleeve functioning, so far 45 as the equalization of air pressures is concerned, as an extension of the grooves. The inlet valve sleeve, it is to be observed, has an imperforate and ungrooved portion inwardly of the inlet ports and immediately 50 adjacent the inward ring head 29 corresponding in location and function to the ungrooved portion of the cylindrical surface between the outward flange 34 and the outward ends of the grooves 36. As before, it 55 is obvious that the inlet valve sleeve and the exhaust valve sleeve may partake of free relative movement as long as the radially inwardly projecting flange 28 of the exhaust valve sleeve is transversing the grooves 36 or 60 the ports 26 of the inlet valve sleeve for the air or other gaseous medium compressed upon the advancing side of the flange 28 is relieved through the grooves 36, and ports 26 to the receding side. When, however, the

flange 28 of the exhaust valve sleeve has 65 traversed the grooves or ports to a point closing their outlets at either end it is obvious that an air cushion will be formed between the opposed parts forming a driving connection without actual metallic contact 70 between them.

Where a vertically disposed cylinder is employed as in the illustrative engine here shown, or where the cylinder is disposed at any angle to the horizontal, the exhaust and 75 inlet valve sleeves are designed to contact with each other and with the cylinder wall and the inlet valve sleeve with the piston with a sufficient frictional engagement to maintain the sleeves in elevated position against 80 gravity when the engine is stopped with the piston out of supporting and driving relation with the sleeves through the flanges already described. In any event also, the sleeves are in sufficiently close contact with 85 each other and with the cylinder wall and piston to provide the substantially air tight sliding engagement already referred to and also to prevent leakage of the gases confined in the combustion chamber of the cylinder. 90 Packing rings 37 and 38 are also provided in the piston head and the inlet valve sleeve.

The ring head 29 of the inlet valve sleeve is designed of such total surface transversely of the combustion cylinder as to function as 95 a piston when impinged upon by the expanding gases upon ignition of the charge to move the valve simultaneously with and the full length of movement of the piston during its ignition or working stroke. This movement of the inlet valve sleeve extends from 100 its position shown in Fig. 2 at the inward limit of its stroke, to its position shown in Fig. 4, at the outward limit of its stroke, and the simultaneous movement of the piston and inlet valve sleeve both independently under the action of the expanding gases during the ignition stroke, maintains the piston and surrounding inlet valve sleeve 105 without relative movement and with their heads in engagement closing the inlet passage for the explosive mixture.

It is to be observed that during a major portion of this simultaneous movement of the inlet valve sleeve outwardly with the piston on its ignition stroke, which simultaneous movement maintains the charge inlet closed, the exhaust valve sleeve must be stationary to maintain the exhaust ports closed, as shown in Fig. 2, also that at the 115 end of the exhaust stroke and upon the beginning of the suction stroke, as shown in Fig. 6, when the parts are in the same initial position as at the beginning of the ignition stroke, and when the piston is about to make its next outward stroke, both sleeves must remain stationary, the exhaust valve sleeve to maintain the exhaust ports all closed and 120 125

the inlet valve sleeve to permit of that relative movement between itself and the piston which opens the charge inlet ports.

While the valve sleeves are in frictional contact with each other and with the cylinder wall and the inlet valve sleeve is also in frictional contact with the piston, as already set forth, such frictional contact is for the purposes already stated and is not relied upon to maintain the exhaust valve sleeve stationary while the piston and inlet valve sleeve move relatively thereto upon the ignition stroke as shown in Fig. 2, nor to maintain both valve sleeves stationary while the piston moves relatively thereto upon the suction stroke as shown in Fig. 7. In fact the frictional resistance to relative sliding movement between the various parts here described is substantially the same in both directions of movement so that its total effect upon a change in direction of movement is negligible. The inertia of the valve sleeve to movement or to change in direction of movement already acquired is the factor relied upon to maintain the exhaust valve sleeve stationary during movement of the inlet valve sleeve with the piston and both valve sleeves stationary during the movement of the piston to open and close the charge inlet ports, within the limits of relative movement permitted by the driving connections already described. For example, the exhaust valve sleeve having been moved inwardly at piston speed to the closed position shown in Fig. 2, and the inlet valve sleeve and piston having also moved inwardly at piston speed upon the next preceding stroke to compress the charge, as will later be more fully set forth, the extremely rapid change in direction of movement of the piston and inlet valve sleeve from inward to outward stroke upon the ignition of the charge, cannot be transmitted to the exhaust valve sleeve in time to overcome the inertia of that sleeve to outward movement through any other means than a driving connection between them, which as will later be observed, does not occur until the major portion of the ignition stroke has been performed.

At the beginning of this ignition or working stroke, the exhaust valve sleeve, as shown in Fig. 2, is at the inward limit of its stroke with the ports 23 therein out of registry with the exhaust ports 7 in the engine cylinder. Due, as already stated to the inertia of the exhaust valve sleeve and the limited freedom of movement permitted between these valve sleeves, the exhaust valve sleeve remains in its inward closing position while the inlet valve sleeve and piston move outwardly the flange 28 upon the outward end of the exhaust valve sleeve describing a relative traversing movement over the exterior cylindrical surface of the inlet valve sleeve

and over the longitudinal pressure equalizing grooves 36 therein, in the manner already described.

The inward and outward flanges or ring heads on the inlet valve sleeve are so spaced apart and from the flange on the end of the exhaust valve sleeve in the initial position of the valves shown in Fig. 2, relative to the length of stroke of these valves and of the piston, that upon the completion of a predetermined portion of the working stroke of the piston, selected in the illustrative embodiment of my invention and as shown in Fig. 3 as three-quarters of the length of that stroke, the inward ring head 29 of the inlet valve sleeve so closely approaches the flange 28 on the exhaust valve sleeve as to cause the latter to close the inward ends of the grooves in the outer cylindrical surface of the inlet valve sleeve, the ports 26 in the inlet valve sleeve here being considered as an extension of the grooves 36. From this point of the ignition or working stroke on to its completion the inlet valve sleeve drives the exhaust valve sleeve through the medium of the entrapped air between their opposed flanges in the manner already described, the exhaust valve sleeve moving from its closed position shown in Figs. 2 and 3 to its open position shown in Fig. 4 with its ports 23 in registry with the exhaust ports 7 in the engine cylinder. The ignition or working stroke of the piston has thus been completed and its return stroke to expel the products of combustion about to begin.

It will also be observed from Fig. 4, that at the completion of the ignition or working stroke, the outward ring head on the inlet valve sleeve is in close approach to the flange 32 on the outward end of the piston skirt with the outward ends of the pressure equalizing grooves 35 closed. Upon the inward movement of the piston on its exhaust stroke the air between the flange 32 on the piston skirt and the ring head 33-34 on the inlet valve sleeve is entrapped and compressed forming a driving connection between the flanges without metallic contact in the manner heretofore described, the piston thus moving the inlet valve sleeve inwardly therewith and to the full extent of the exhaust stroke from the position shown in Fig. 4 to that shown in Fig. 6. The inlet valve sleeve and the piston still remaining without relative movement.

At the completion of the ignition stroke and the beginning of the exhaust stroke, as shown in Fig. 4, the exhaust valve is open and its flange 28 at the inward end of the cylindrical surface of the inlet valve sleeve remote from the driving flange 34, so that the exhaust valve sleeve remains in outward open position while the piston and inlet valve sleeve travel inwardly.

Because of the relative disposition of the flanges as already stated, the piston driving the inlet valve sleeve inwardly completes the major portion of its exhaust stroke, shown in the illustrative embodiment of my invention as three-quarters of its exhaust stroke, before the flange 34 on the outward end of the inlet valve sleeve comes into driving relation with the flange 28 on the end 5 of the exhaust valve sleeve, as shown in Fig. 5. From this point on to the completion of the exhaust stroke the piston, inlet valve sleeve and exhaust valve sleeve move inwardly in unison, the exhaust valve sleeve moving to its closing position shown in 10 Fig. 6.

Fig. 6 also shows the position of the parts at the beginning of the next succeeding stroke, the suction or charging stroke, and 15 it is to be observed that there are no flanges in sufficiently close approach to form a driving connection for outward movement of the valve sleeves. During the suction stroke there is, of course, no pressure due to the 20 expansive force of a gaseous medium to be exerted either upon the piston or the ring head of the inlet valve sleeve to drive the same, the movement of the piston being imparted thereto from the crank shaft because 25 of the momentum acquired upon the ignition stroke. Because of the extremely rapid change in direction of movement of the piston from in stroke to out stroke, in effect pulling the piston through the inlet valve 30 sleeve before the change of motion can be imparted to that sleeve due to the inertia of the same, as already stated, the inlet valve sleeve remains in the position it had 35 attained at the end of the exhaust stroke.

40 This suction stroke marks the first relative movement between the piston and the inlet valve sleeve. As soon as the piston passes through the inlet valve sleeve a sufficient distance to expose the piston head outwardly 45 of the inward edge of the ports 26 in the inlet valve sleeve, or otherwise expressed, a sufficient distance to uncover the ports 26, the carburetor or other charge forming device and the crank case, which is in effect 50 so far as the delivery of the charge is concerned the connecting charge inlet manifold, are subject to the vacuum created in the cylinder by the descending piston, and the charge is drawn inwardly through the interior 55 of the piston, out through the ports 27 therein, through the ports 26 in the inlet valve sleeve and inwardly over the piston head to the interior of the engine cylinder.

60 This relative movement between the piston and the charge inlet valve sleeve, the valve sleeve remaining stationary and the piston descending, continues during an initial portion 65 of the suction stroke, shown in the illustrative embodiment of my invention as the first quarter of the suction stroke of the

piston until the sleeve and piston have attained the relative positions shown in Fig. 7, and which mark the fullest extent of opening of the charge inlet valve since the piston has traversed the ports 26 in the inlet valve 70 and any further relative movement would bring the ports 27 in the piston out of registry with the ports in the valve. This position also marks the approach of the shoulder 31 on the piston into pneumatic driving relation with the inwardly disposed flange 33 on the end of the inlet valve sleeve, and from this point on to the end of the suction stroke shown in Fig. 8, the piston and the inlet valve sleeve move in unison, 75 the relative movement of the piston and inlet valve sleeve ceasing so that for the remainder of the suction stroke the inlet valve remains in its fullest open position relative to the charge delivery ports in the 80 piston, with the result that the charge is delivered to the cylinder substantially throughout the entire suction stroke of the piston.

It is to be observed that during the entire 90 suction stroke from the position of the parts as shown in Fig. 6 to those as shown in Fig. 8, the exhaust valve remains in its inward closed position due to the fact that the inlet valve sleeve descended with the piston only 95 during the last portion of its stroke, shown in the illustrative embodiment in Fig. 8 as the last three-quarters of the piston stroke and hence did not move a sufficient extent to bring its inward ring head 29 into driving engagement with the flange on the outward end of the exhaust valve sleeve, until the end of the suction stroke was reached, as shown in Fig. 8.

The next succeeding stroke of the piston is 105 that compressing the charge introduced into the cylinder and begins from the position of the parts shown in Fig. 8 and ends with the parts in position shown in Fig. 2, when the cycle of operations is completed.

Upon the beginning of the compression stroke, as shown in Fig. 8, the outward flange 32 on the piston is not in driving relation with the ring head 33—34 on the inlet valve sleeve and does not come into such driving relation until a portion of the compression stroke is completed, shown in the illustrative embodiment of my invention as the first quarter as indicated in Fig. 9. Hence during the first quarter of this stroke, 115 the inlet valve sleeve, because of its inertia, as already stated, remains stationary while the piston in rapid change of direction moves relatively thereto. It is also to be observed that it is this relative movement which closes 120 the charge inlet ports so that for a brief portion of the compression stroke of the piston the inlet ports are open. This continuance of the opening of the charge inlet ports into the compression stroke does not, however, re- 125 130

duce the total quantity of the charge delivered to the engine cylinder but rather augments the same due to the momentum of the rapidly moving inlet stream.

- 5 Upon the completion of this initial portion of the compression stroke and the bringing of the piston to a position closing the inlet ports as shown in Fig. 9, the piston and inlet valve sleeve move inwardly in unison 10 for the remainder of the stroke due to the approach of the flange 32 of the piston into driving relation with the ring head 33—34 of the inlet valve sleeve.

The exhaust valve, it is to be observed, is 15 not moved during this compression stroke from the closed position it had previously attained, due to the fact that during the movement of the inlet valve sleeve on this stroke its inward flange 29, which forms the 20 only driving member for moving the exhaust valve to open position, is being moved out of instead of into driving relation with the exhaust valve sleeve flange 28.

It is obvious that what has been here 25 termed the piston with its head subject to the direct impingement thereon of the expanding gases of combustion and with its hollow cylindrical skirt having ports for the delivery of the explosive mixture from its 30 interior, performs functions additional to the customary functions of a working piston, performing in fact the functions of a combined working and charge distributing piston. Or, the hollow cylindrical skirt portion 35 of the piston with its charge delivery ports cooperating with the surrounding inlet valve sleeve may be considered as functioning as and may be regarded as one part of a two-part charge inlet valve, the second part 40 being the inlet valve sleeve itself.

Obviously the present invention is not limited to the specific embodiment illustrated and described but features of the invention are susceptible of embodiment in various devices and may be advantageously used in 45 various combinations and sub-combinations.

Having now described my invention I claim:

1. In a four stroke cycle internal combustion engine, the combination with a cylinder, 50 a working piston reciprocating therein, an exhaust valve and a charge inlet valve, means mounted upon and operated by the piston and mechanically operating upon the said exhaust and charge inlet valves to close the exhaust valve on one stroke of said piston, to open the charge inlet valve on the next succeeding stroke of said piston, and to close the charge inlet valve on the second 55 succeeding stroke of said piston.

2. In a four stroke cycle internal combustion engine, the combination with a cylinder provided with an exhaust port and a charge inlet port, a working piston reciprocating 60 therein, means mounted upon and operated

by the piston to close the exhaust port on one stroke of said piston, to open the charge inlet port on the next succeeding stroke of said piston, and to close the charge inlet port on the second succeeding stroke of said piston, 70 said means including exhaust and inlet valves in sliding engagement with said cylinder and moved by said piston.

3. In a four stroke cycle internal combustion engine, in combination with a cylinder, a single working piston reciprocating therein having a charge delivery passage, a single charge inlet valve mounted for reciprocating movement in said cylinder and cooperating with said piston by relative movement 75 therewith in one direction to open said charge delivery passage and by relative movement in the opposite direction to close said passage and by simultaneous movement with said piston and at piston speed to maintain 80 said passage open or closed during the reciprocation of said piston, and means for producing said relative movements in the direction to open said passage during the suction stroke, in the direction to close said 85 passage during the compression stroke and said simultaneous movement to maintain said passage in closed position during the explosion and exhaust strokes.

4. In an internal combustion engine, in 90 combination with a cylinder, a working piston reciprocating therein, a two part valve mounted in said cylinder, the two parts relatively movable in opposite directions in 95 sliding engagement in the line of reciprocation of said piston to open and close said valve and movable simultaneously and together in the same direction in the line of movement of said piston to maintain said valve in open or closed position, means causing 100 the reciprocation of one of said parts with said piston, driving means associated with said parts in their closed position and operating only in one direction of movement of said piston to move said parts simultaneously and together with said piston.

5. In an internal combustion engine, in combination with a cylinder, a piston reciprocating therein, a two part valve mounted in said cylinder, the two parts relatively 115 movable in opposite directions in the line of reciprocation of said piston to open or close said valve and movable simultaneously and together in the line of reciprocation of said piston to maintain said valve in open or closed position, means causing the reciprocation of one of said parts with said piston, driving means associated with said parts in 120 their open position and operating only in one direction of movement of said piston to move said parts simultaneously and together with said piston.

6. In an internal combustion engine, in combination with a cylinder, a working piston reciprocating therein, a two part charge 125

65 piston reciprocating therein, means mounted upon and operated

- 8
- inlet valve, the two parts relatively movable in sliding engagement in opposite directions to open and close said inlet valve, means associated with said parts limiting their relative movement to completely open or completely closed position, means causing the reciprocation of one of said parts with the working piston, the other of said parts designed to slidably engage the cylinder walls.
- 5 7. In a four stroke cycle internal combustion engine, in combination with a cylinder, a working piston reciprocating therein, a two part charge inlet valve, the two parts relatively movable in sliding engagement in opposite directions in the line of reciprocation of said piston to open and close said inlet valve, and simultaneously movable together and in the same direction to maintain said valve in open or closed position, means causing the reciprocation of one of said parts with said piston, driving means associated with said parts in their closed position and operating only on the inward stroke of said piston to move said parts simultaneously and together with said piston.
- 10 8. In a four stroke cycle internal combustion engine, in combination with a cylinder, a working piston reciprocating therein, a two part charge inlet valve the two parts relatively movable in sliding engagement in opposite directions in the line of reciprocation of said piston to open and close said inlet valve, and movable simultaneously and together in the same direction in the line of reciprocation of said piston to maintain said valve in open or closed position, means causing the reciprocation of one of said parts constantly with said piston, driving means associated with said parts in their open position and operating only on the outward stroke of said piston to move said parts simultaneously and together with said piston.
- 15 9. In a four stroke cycle internal combustion engine in combination with a cylinder, a working piston reciprocating therein, a two part charge inlet valve having ports extending in the line of reciprocation of said piston a substantially less distance than the length of the piston stroke, the two parts relatively movable in opposite directions in the line of reciprocation of said piston to open and close said ports, and movable simultaneously and together in the same direction in the line of reciprocation of said piston to maintain said ports in open or closed position, means causing the reciprocation of one of said parts constantly with said piston, driving means associated with said parts in their closed position and operating only on the inward stroke of said piston to move said parts simultaneously and together with said piston, said valve part not constantly reciprocating with said piston designed to be moved simultaneously and together with said piston upon its ignition stroke by direct impingement of the expanding gases of combustion on said last mentioned valve part.
- 20 10. In an internal combustion engine, in combination with a cylinder, a working piston reciprocating therein, a two part charge inlet valve having ports extending in the direction of movement of the piston, a substantially less distance than the length of the piston stroke, the two parts relatively movable in sliding engagement in opposite directions to open and close said ports, means associated with said parts limiting their relative movement to open and closed position of said ports, means causing the reciprocation of one of said parts by and with the working piston, the other of said parts designed to slidably engage the cylinder walls.
- 25 11. In an internal combustion engine, in combination with a cylinder, a working piston reciprocating therein, a two part charge inlet valve, said parts being relatively movable in opposite directions in the line of reciprocation of said piston to open and close said valve, means moving one of said parts toward open position of the valve upon each outward stroke of said piston, the other of said parts designed to be moved in said direction of movement of said first mentioned part by the direct impingement thereon of the expanding gases of combustion.
- 30 12. In a four stroke cycle internal combustion engine, in combination with a cylinder, a working piston reciprocating therein, a two part charge inlet valve having ports extending in the line of reciprocation of said piston a substantially less distance than the length of the piston stroke, the two parts relatively movable in sliding engagement in opposite directions in the line of reciprocation of said piston to open and close said ports and movable simultaneously and together in the line of reciprocation of said piston to maintain said ports in open or closed position, means causing the constant reciprocation of one of said parts with said piston, driving means associated with said parts in their open position and operating only on the outward stroke of said piston to move said parts simultaneously and together with said piston, driving means associated with said parts in their closed position and operating only on the inward stroke of said piston to move said parts simultaneously and together with said piston, said valve part not constantly reciprocating with said piston designed to be moved simultaneously and together with said piston upon its ignition stroke by direct impingement of the expanding gases of combustion on said last mentioned valve part.
- 35 13. In an internal combustion engine, in combination with a cylinder, a working

- piston reciprocating therein, a two part charge inlet valve, said valve parts relatively movable in opposite directions in the line of reciprocation of said piston for opening and closing said inlet valve, means moving one of said valve parts toward open position of the valve upon each outward stroke of the piston, the other of said valve parts being mounted in sliding engagement with 5 said cylinder wall and designed to move in said sliding engagement with said cylinder walls in the direction of movement of said first mentioned valve part by direct impingement on said other valve part of the expanding gases of combustion.
14. In an internal combustion engine, in combination with a cylinder, a working piston reciprocating therein, a two part charge inlet valve, said parts being relatively movable in opposite directions in the line of reciprocation of said piston to open and close said valve and simultaneously movable in the same direction to maintain said valve in open or closed condition, one of 10 said valve parts remaining normally stationary, means moving the other of said valve parts with said piston whereby the outstroke of said piston relatively moves said parts to open position and the return stroke of said piston relatively moves said parts to closed position, the first mentioned of said valve parts designed to be moved simultaneously with said piston upon its ignition stroke by direct impingement of the expanding gases 15 of combustion on said first mentioned valve part.
15. In an internal combustion engine, the combination with a cylinder, a combined working and hollow distributing piston reciprocating in said cylinder and having a piston head and charge distributing ports adjacent thereto, means mounted upon and operated by the combined working and distributing piston to expose the charge distributing ports to the engine cylinder on one stroke and to close said charge distributing ports on the next succeeding stroke, said means including a slide valve normally stationary in sliding contact with said cylinder 20 until moved by said piston.
16. In an internal combustion engine, in combination with a cylinder, a combined working and distributing piston reciprocating said cylinder having charge delivery ports, an inlet valve sleeve surrounding said piston having ports of greater extent in the line of reciprocation of said piston than said delivery ports in said piston but of substantially less extent than the length of stroke of 25 said piston, said piston and valve sleeve being relatively movable in sliding engagement in opposite directions in the line of reciprocation of said piston to open and close said ports.
17. In an internal combustion engine, in combination with a cylinder, a combined working and charge distributing piston reciprocating therein and having a piston head and charge delivery ports therewith, a slide valve sleeve in said cylinder surrounding 30 said working and distributing piston and having a ring head and ports adjacent thereto elongated in the line of movement of said piston to extend in the relative open position of the valve and piston from a point in registry with said delivery ports in said piston to a position inwardly and clearing said ring head from said piston head, said piston and valve sleeve being capable of relative movement from the aforesaid open position to closed position with said ring head in sliding engagement with said piston head, said valve sleeve in the latter relative position of the parts designed to partake of a like movement with said piston upon its ignition 35 stroke by direct impingement of the expanding gases of combustion upon said ring head.
18. In a four stroke cycle internal combustion engine, in combination with a cylinder, a combined working and charge distributing piston reciprocating therein having delivery ports for the explosive mixture, an inlet valve sleeve surrounding said piston having ports of greater extent in the line of reciprocation of said piston than said delivery ports in said piston but of substantially less extent than the length of stroke of said piston, said piston and valve sleeve being relatively movable in sliding engagement in opposite directions 40 in the line of reciprocation of said piston to open and close said ports, means associated with said piston and valve sleeve limiting their relative movement to complete open or closed position of said ports, said valve sleeve designed to be normally 45 stationary in sliding engagement with said cylinder wall whereby the reciprocatory movement of said piston opens and closes said ports.
19. In a four stroke cycle internal combustion engine, in combination with a cylinder, a combined working and charge distributing piston reciprocating therein having delivery ports for the explosive mixture, an inlet valve sleeve surrounding said piston having ports designed to open and close communication between said delivery ports and the interior of said cylinder, said piston and valve sleeve designed for relative movement 50 in sliding engagement in opposite directions in the line of reciprocation of said piston to open and close said communication, and for simultaneous movement together thereafter to maintain said piston and valve sleeve in relative positions of open and closed communication, driving means associated with said piston and valve sleeve in their closed position and operating only in one direction.

tion of movement of said piston to move said valve sleeve simultaneous and together with said piston.

20. In a four stroke cycle internal combustion engine, in combination with a cylinder, a combined working and charge distributing piston reciprocating therein having delivery ports for the explosive mixture, an inlet valve sleeve surrounding said piston 5 having ports designed to open and close communication between said delivery ports and the interior of said cylinder, said piston and valve sleeve designed for relative movement in sliding engagement in opposite directions in the line of reciprocation of said piston to open and close said communication, and for simultaneous movement together to maintain said piston and valve sleeve in relative positions of opened and 10 closed communication, driving means associated with said piston and said valve sleeve in their open position and operating only in one direction of movement of said piston to move said valve sleeve simultaneously 15 and together with said piston.

21. In a four stroke cycle internal combustion engine, in combination with a cylinder, having an exhaust port, a valve movable to open and close said port, a combined 20 working and charge distributing piston reciprocating therein having delivery ports for the explosive mixture, an inlet valve sleeve surrounding said piston having ports designed to open and close communication 25 between said delivery ports and the interior of said cylinder, said piston and valve sleeve designed for relative movement in sliding engagement in opposite directions in the line of reciprocation of said piston to open and close said communication, and for simultaneous movement thereafter to maintain said relative positions, means associated with said piston and valve sleeve limiting their relative movement to complete open 30 or closed positions of said ports, said valve sleeve designed to be normally stationary in sliding engagement with said cylinder wall whereby the initial movement of said piston on the suction stroke opens said ports and 35 the initial movement of said piston on its returning stroke closes said ports, said valve sleeve designed to move initially and simultaneously with said piston on its ignition stroke by the direct impingement of the expanding products of combustion on said valve sleeve, means associated with said valve sleeve operated by its full length movement with said piston on its ignition stroke to open said exhaust valve.

60 22. In a four stroke cycle internal combustion engine, in combination with a cylinder having an exhaust port, a valve movable to open and close said exhaust port, a combined working and distributing piston reciprocating in said cylinder, having charge

delivery ports, an inlet valve sleeve surrounding said piston having ports of greater extent in the line of reciprocation of said piston than said delivery ports in said piston but of substantially less extent than the 70 length of stroke of said piston, said piston and valve sleeve being relatively movable in sliding engagement in opposite directions in the line of reciprocation of said piston to open and close said ports, said valve sleeve 75 designed to be normally stationary in sliding engagement with said cylinder wall during that part of the piston stroke in each direction required to bring said piston and valve into relative positions of open and closed 80 ports, means associated with said piston and valve sleeve in the relative position of open ports to drive said valve sleeve with said piston on its outward stroke, means associated with said piston and valve sleeve in 85 the relative position of closed ports to drive said valve sleeve with said piston on its inward stroke, said valve sleeve designed to move in said sliding engagement with said cylinder wall initially and simultaneously 90 with said piston throughout its ignition stroke by the direct impingement of the expanding products of combustion on said valve sleeve, means associated with said valve sleeve operated by its full length movement 95 with said piston on its ignition stroke to open said exhaust valve, and means associated with said valve sleeve operated upon its inward movement with said piston to close said exhaust valve.

100 23. In a four stroke cycle internal combustion engine, in combination with a cylinder, having an exhaust port, a valve movable to open and close said port, a working piston reciprocating therein, a two part charge inlet valve having ports extending in the line of movement of said piston substantially a less distance than the length of the piston stroke, the two parts relatively movable in sliding engagement in opposite directions 105 in the line of reciprocation of said piston to open and close said ports, means associated with said valve parts limiting their relative movement to complete open and closed position of said ports, means causing the reciprocation of one of said valve parts with the working piston, said other valve part designed to be normally stationary in sliding engagement with said cylinder wall during the initial movement of said first mentioned valve part with said piston on its suction stroke to open said ports and during the initial movement of said first mentioned valve part with said piston on its next return or compression stroke to close said ports 110 whereby said second mentioned valve part describes strokes in opposite directions less than the corresponding strokes of said piston and first mentioned valve part, said second mentioned valve part designed to 115 120 125 130

- move in said sliding engagement with said cylinder wall initially and simultaneously with said piston throughout its ignition stroke by the direct impingement of the expanding products of combustion on said second mentioned valve part, means associated with said second mentioned valve part operated by its full length movement with said piston on its ignition stroke to open 5 said exhaust valve, and means associated with said second mentioned valve part and operated by its return stroke with said piston to close said exhaust valve.
24. In a four stroke cycle internal combustion engine, the combination with a cylinder having an exhaust port, a valve movable to open and close said exhaust port, a working piston reciprocating in said cylinder, means mounted upon and operated by the 10 piston only on its exhaust stroke to move said valve to close said exhaust port, and means operating independently of said piston only by the expanding gases of combustion 15 on the ignition stroke to move said valve to open said exhaust port.
25. In a four stroke cycle internal combustion engine, the combination with a cylinder having an exhaust port, a working piston reciprocating in said cylinder, means 20 mounted upon and operated directly by the piston to close said exhaust port, said means including an exhaust valve sleeve normally stationary in slidable engagement with said cylinder wall until moved by said piston only upon its exhaust and ignition strokes.
26. In a four stroke cycle internal combustion engine, the combination with a cylinder having an exhaust port, a working piston reciprocating in said cylinder, an exhaust valve normally stationary in slidable engagement with said cylinder wall and movable in opposite directions to open and close said exhaust port, means mounted 30 upon and operated by the piston only on its exhaust stroke to move said exhaust valve to close said exhaust port, and means operating independently of said piston only by the expanding gases of combustion on the ignition stroke to move said valve to open 35 said exhaust port.
27. In a four stroke cycle internal combustion engine, the combination with a cylinder having an exhaust port, an exhaust valve sleeve normally stationary in sliding 40 engagement with said cylinder wall and movable in opposite directions to open and close said exhaust port, a working piston reciprocating in said cylinder, means mounted upon and operated by said piston on its exhaust stroke to move said exhaust valve sleeve to close said exhaust port, and means operated only by the expanding gases 45 of combustion on the ignition stroke to move said valve sleeve to open said exhaust ports, said means including a cylindrical sleeve 50
- mounted in said cylinder and designed to be frictionally held against said cylinder wall until moved by the direct impingement thereon of the expanding gases of combustion.
28. In an internal combustion engine, in combination with the combustion chamber having an exhaust port, a working piston therein, a valve movably mounted to open and close said exhaust port, and means operating on the ignition stroke of said piston to move said valve to open said exhaust port and on the next succeeding stroke of said piston to move said valve to close 70 said exhaust port, said means including an element freely slidable between said piston and said valve, designed for movement in the direction of the ignition stroke of said piston solely by the direct impingement on said element of the expanding gases 75 of combustion and means associated with said piston for the return of said element to initial position upon the return stroke of said piston.
29. In an internal combustion engine, in combination with the combustion cylinder having an exhaust port, a working piston reciprocating therein, a valve movably mounted to open said exhaust port in one direction of movement and to close said exhaust port in the opposite direction of movement, an element independently mounted in said chamber for like reciprocatory movement with said piston designed to be moved simultaneously with said piston upon its ignition stroke by direct impingement on said element of the expanding gases of combustion, means associated with said piston for the return of said element to its initial position upon the return stroke of said piston, and driving means associated with said element imparting reciprocatory movement to said exhaust valve.
30. In an internal combustion engine, in combination with the combustion chamber having an exhaust port, a working piston thereon, a valve movably mounted to open and close said exhaust port, and means operating on the ignition stroke of said piston to move said valve to open said exhaust port and on the next succeeding stroke of said piston to move said valve to close said exhaust port, said means including an element mounted in and movable in said cylinder designed for movement in one direction to impart closing movement to said exhaust valve by the direct impingement on said element of the expanding gases of combustion.
31. In a four stroke cycle internal combustion engine, in combination with an engine cylinder, a working piston reciprocating therein, a cylindrical sleeve element mounted in said cylinder surrounding said piston and in sliding engagement with the

walls of said cylinder and piston, said cylindrical sleeve element designed to partake of like movement with said piston upon its ignition stroke by direct impingement of the expanding gases of combustion on said element and means associated with said piston returning said element to its initial position with the return stroke of said piston, an exhaust valve and means to open and close said exhaust valve by the movement of said cylindrical sleeve element.

32. In an internal combustion engine, in combination with an engine cylinder having an exhaust port, a working piston reciprocating in said cylinder, a cylindrical valve sleeve mounted in said cylinder in sliding engagement longitudinally of said cylinder walls to open said exhaust port by movement in the direction of the ignition stroke of said piston and to close said exhaust port by movement in the direction of the return stroke of said piston, a cylindrical sleeve element mounted in said cylinder within said valve sleeve and surrounding said piston, said cylindrical sleeve element designed to be moved simultaneously with said piston upon its ignition stroke by direct impingement on said element of the expanding products of combustion, means associated with said piston for the return of said element to its initial position with the return stroke of said piston, and means associated with said element and with said valve sleeve to impart like movement from said element to said valve sleeve during the latter part of the ignition and return strokes of said element, said means including oppositely disposed flanges on said cylindrical valve sleeve and on said cylindrical sleeve element spaced apart a predetermined distance to bring a flange on each into driving relation with a flange on the other just prior to the completion of the ignition and return strokes of said piston and said cylindrical sleeve element.

33. In an internal combustion engine, in combination with an engine cylinder having an exhaust port, a working piston reciprocating therein, a valve closure movable in the direction of the ignition stroke of said piston to open said exhaust port and in the direction of the return stroke of said piston to close said exhaust port, an element independently mounted in said cylinder for like reciprocating movement with said piston, and designed to be moved simultaneously with said piston upon the ignition stroke by direct impingement on said element of the expanding gases of combustion, means associated with said piston for the return of said element to its initial position with the return stroke by said piston, and means associated with said element and with said valve closure to impart like movement from said element to said valve closure during the

latter part of the ignition and return strokes of said element, whereby the exhaust port is opened during the latter part of the ignition stroke of said piston and closed during the latter part of its return stroke.

34. In an internal combustion engine, in combination with an engine cylinder, a cylindrical element moving therein under the direct impingement thereon of the expanding gases of combustion radially outwardly disposed annular projections on the cylindrical surface of said element spaced apart longitudinally thereof, said cylindrical surface being provided with grooves between said annular projections, extending longitudinally thereof and terminating short of the annular projections to provide an annular ungrooved portion of the cylindrical surface of said cylindrical element adjacent each said annular projection, a cylindrical valve sleeve mounted in said cylinder, surrounding said cylindrical element and having its interior surface in substantially air-tight sliding engagement with one of said annular projections on said cylindrical element, and having a radially inwardly disposed annular shoulder in substantially air-tight sliding engagement with said cylindrical surface of said cylindrical element between said annular projections thereon.

35. In an internal combustion engine, in combination with an engine cylinder, a cylindrical valve sleeve mounted in said cylinder in frictional sliding contact with the cylinder wall, said valve sleeve having at one extremity a radially inwardly disposed annular flange, a cylindrical element moving thereon by the direct impingement thereon of the expanding gases of combustion, radially outwardly disposed annular flanges on the cylindrical surface of said element spaced apart longitudinally thereof, one of said annular flanges on said cylindrical element engaging in substantially air-tight sliding contact the interior wall of said valve sleeve on one side of the radially inwardly disposed annular flange on said valve sleeve, the other of said annular flanges on said cylindrical element engaging in substantially air-tight contact the interior surface of the cylinder on the opposite side of said annular flange on said valve sleeve, the outer surface of said cylindrical element opposed to said valve sleeve having grooves extending longitudinally thereof between and terminating short of said annular projections thereon to provide a grooved portion and an annular ungrooved portion of the cylindrical surface of said element adjacent each said annular projection thereon.

36. In an internal combustion engine, in combination with an engine cylinder, a working piston reciprocating therein having a piston head and a cylindrical side wall of two portions of unequal diameters sepa-

- rated by an annular shoulder at right angles thereto, and having an annular flange at the outer extremity of the side wall portion of reduced diameter, said flange engaging the cylinder wall in sliding substantially air-tight engagement, and spacing said portions of said piston wall of unequal diameters unequal distances from said cylinder wall, a cylindrical valve inlet sleeve 5
10 rounding said piston and having its interior surface in substantially air-tight sliding contact with the cylindrical piston wall of greater diameter, said inlet valve sleeve having at one end a radially inwardly disposed annular flange in substantially air-tight slid-

ing engagement with the piston wall of reduced diameter, the cylindrical surface of said piston of reduced diameter being provided with grooves extending longitudinally thereof and terminating short of said annular shoulder and said annular flange on said piston to provide an annular ungrooved portion of the cylindrical surface of said piston of reduced diameter adjacent said annular shoulder and said annular flange thereon. 20
25

In testimony whereof, I have signed my name to this specification, this 16th day of October, 1919.

ALBERT W. CHASE.
